DEVICE FOR DISPENSING LIQUID OR PLASTIC MATERIALS.

1,299,487.

Specification of Letters Patent.

Patented Apr. 8, 1919.

Application filed September 18, 1918. Serial No. 254,686.

To all whom it may concern:

Be it known that I GUSTAVE A. LOEBEN, a citizen of the United States, and a resident of Philadelphia, in the county of Philadelphia and State of Pennsylvania, have invented an Improvement in Devices for Dispensing Liquid or Plastic Materials, of which the following is a specification.

My invention relates to devices for dispensing liquids, semi-liquids and plastic materials and it is adapted for use in the dispensing of such materials of various kinds and for various purposes. I have shown the same, however, as employed in connection 15 with a shaving brush for which I have found it well adapted.

One of the difficulties with devices of this character as heretofore manufactured and which have been employed in the construction 20 of fountain shaving brushes has been that of preventing the semi-liquid or plastic soap from escaping into the operative part of the device and preventing satisfactory operation of the same.

One of the objects of my invention is to 25 overcome this difficulty by providing an efficient and positive means for preventing the soap material or other material, as the case may be, from escaping into or between the relatively movable operating parts of the device thereby insuring that the said parts shall at all times function satisfactorily and efficiently.

A further object of my invention is to 30 provide a construction in which the valve controlled discharge opening leading from the handle in which the liquid, semi-liquid or plastic materials are contained, is automatically and positively opened and closed 35 during the operation of the device in such manner as to permit the required portions of material to be discharged but to prevent the discharge of any portion which is not desired for immediate use. If portions not required 40 for immediate use were discharged they would become hard and unusable and would interfere with the proper and efficient operation of the device.

A further object of my invention is to 45 provide a construction which is more compact and in which the operative parts are so combined and related to each other that they are caused to occupy a smaller space than heretofore has been practicable.

A still further object of my invention is to

provide the piston, which operates in the handle for expelling therefrom the material which is to be dispensed, with means for preventing the escape of any portion of the said material between the said piston and the 60 means for causing movement thereof longitudinally of the said handle.

Other objects and advantages of my invention will be pointed out particularly and referred to in the detailed description thereof 65 which follows or will be apparent from said description.

In order that my invention may be more readily comprehended and its commercial and practical uses more fully appreciated, 70 reference may be had to the accompanying drawing in which I have illustrated one form of a convenient embodiment thereof. Various changes may be made in the details of construction without departing from the 75 principles of my invention.

In the drawing:—

Figure 1 is a longitudinal sectional view of a fountain shaving brush in which the dispensing portion is constructed in accordance 80 with my invention;

Fig. 2 is a transverse sectional view taken on the line 2—2 of Fig. 1; and

Fig. 3 is a sectional view taken on the line 3—3 of Fig. 2 and showing a detail of construction.

Referring to the drawing, 1 designates a hollow handle which also constitutes the reservoir for holding the material to be dispensed. The outer rear end portion of the 90 said handle is enlarged as indicated at 2 for a purpose to be hereinafter indicated and is closed, as indicated at 3,—the closure in the construction shown being integral with the body of the handle. However, this need not 95 be the case, because the closure may consist of a separate cap sealed or otherwise secured to the end of the handle.

The inner end of the handle 1 is closed by a cap 4 having a flange 5 which is screw 100 threaded for detachable engagement with the screw threaded portion 6 at the inner end of the said handle.

The inner or rear ends of the hairs constituting the brush 7 are secured within the 105 annular opening of a head 8, the forward end of which is bent and finished in the form of an annular enlargement or bead, as indicated at 9. The inner or rear side of said enlargement or bead constitutes a shoulder. 110

The head 8 is adapted to have detachable screw threaded connection with the screw threaded annular flange 9^a of the member 10. The latter is secured at 11 to a shoulder 5 formed at the inner rear end of a tubular member 12 the outer forward end of which is provided with an opening 13 which opening is adapted to be closed by the lower end 14 of a discharge tube leading from the interior of the handle 1. The portion 15 of the said tube which extends into the tubular member 12 is relatively small as compared with the screw threaded portion 16 of the said tube which is situated in the handle 1. 10 15 The portions 15 and 16 may be constructed integrally or separately as in the construction shown.

At its inner rear end of the tubular portion 12 is enlarged as indicated at 20 for the reception of suitable packing material 21 which is situated in the annular space within the enlarged portion 20 surrounding the portion 15 of the discharge tube or passageway.

A gland 24 which has screw threaded connection with interior threads upon the enlarged portion 20 is adapted to compress and hold the packing material 21 securely and tightly in place against a portion of the exterior surface of the part 15 of the discharge 25 30 tube or passageway. It will be observed that the discharge tube is provided with openings at 25 for the discharge of the material 26 therefrom. After the discharge of the material from these openings it escapes 35 through the opening 13 to the brush 7.

30 designates a member which is permanently and fixedly or rigidly secured to the tubular passageway for conveying material to be dispensed from the reservoir. The 40 member 30 is provided with an enlarged forwardly extending portion which is hollowed out as indicated to form a chamber 32,—the hollowing out of the same, forming what may be described or defined as a skirt 33. 45 The skirt 33 is provided with a laterally extending flange 34 as shown. The enlarged portion 20 together with the gland 24 telescopically project into the chamber 32 within in the skirt 33.

50 35 designates an annular spacing member reduced at its upper end as shown to form a shoulder 36. The forward end of the annular member 35 rests against the member 10 while the rear inner end thereof rests 55 against the inner surface of a member 40, the latter being provided with a flange 40^a which has screw threaded connection with the inner rear end of an annular covering member 41. The forward end of the annular member 41 is smooth and extends around and covers and is secured to the screw threaded flange 9^a of the member 10.

The member 40 is provided with a central substantially square opening 42 in which the 60 intermediate portion of the member 30 is

situated. The said member 30 may move longitudinally through the said opening 42 but cannot rotate with respect thereto.

The closing cap member 4 is provided with a central opening as indicated at 45 through 70 which the rear end portion of the member 30 extends, the said member being provided with a shoulder against which the forward side of said member 4 surrounding the opening 45 is seated. The cap member 4 is rotatably secured in position upon the member 30 by a nut 46 which has screw threaded engagement with a reduced portion 47 of the member 30. 75

The member 40 is provided at intervals 80 with depressed inclined portions 50 which constitute cams for coöperating with correspondingly shaped and formed cam projections 51 upon the forward side of the handle closing cap 4. It will be observed that in 85 the present construction I have shown two cam surfaces 50 and also two coöperating cam projections 51. It will be understood, however, that a greater number of such cam acting parts may be provided if desired, depending upon the amount of material it is desired to discharge at intervals from the interior of the handle. 90

It will be noted that I have provided a coil spring 56 which is situated in the annular space between the spacing member 35 and the skirt 33. The forward end of this spring is seated against the annular flange 34 while the rear end thereof is seated against the shoulder 36 formed at the rear upper end portion of the annular spacing member 35. It will be observed that when once screwed in position the portions 10, 40 and 41 are fixed with respect to each other, that is to say, immovable longitudinally. 95 100 105

The screw threaded flange 40^a of the member 40, as well as the screw threaded flange 5 of the cap 4 when the parts are in operative position with the cam projections 51 seated against the cam surfaces 50, is covered and protected by means of an annular covering and protecting member 54. The said member 54 is provided with a short inturned flange 55 which is seated against the outer periphery of the member 41 at a point just 110 forward of the forward edge of the flange 40^a. Said member 54 is also provided with an annular inwardly extending projection 56 which is situated just in rear of the outer peripheral edge of the member 40. In this 115 way the member 54 is permanently secured to the part 40.

The piston which operates interiorly of the handle 1 is provided with a metallic portion 60 having a screw threaded hub 61 120 which is in a screw threaded engagement with the screw threaded portion 16 of the tubular passageway leading from the handle 1. The outer peripheral edge of the said member 60 is provided with spring fingers 125 130

62 which contact with and press against the interior surface of the handle 1. The said piston also comprises an elastic member 62^a which is seated against the metallic plate 5 member 60 and is provided with a central opening 63 through which the hub 61 extends. In order to form a tight joint between the elastic disk 62^a and the screw threaded portion 16, I have provided the 10 said disk at its inner annular rear edge with an inwardly extending annular flange portion 64 which extends over the rear edge of the hub 63 and contacts firmly with and against the screw threaded portion 16 so as to prevent the escape of any of the material 15 26 from the handle 1 between the screw threaded portion 16 and the hub 61.

Assuming that the handle is provided with a supply of liquid, semi-liquid or plastic material, such as soap, 26, as indicated in Fig. 1 of the drawing, the device will be operated to cause a discharge of the quantity of material desired by holding in one hand the portion 41, which, together with the 20 parts connected therewith, may be termed the body portion of the brush-holding section, and taking hold of the handle 1 with the other hand and turning the same together with the cap 4 secured to the inner forward 25 end thereof to the right in the direction in which the hands of a watch turn. Such turning movement causes the cam projections 51 to slide upwardly upon the cam surfaces 50 so as to cause a longitudinal movement of the handle 1, the cap 4 and the discharge 30 tube consisting of the parts 15 and 16. Such movement causes disengagement of the inner forward end 14 of the part 15 from the edges of the opening 13 so that the latter is 40 opened.

By reason of the friction between the spring fingers 62 and the disk 62^a with the interior of the handle 1, it will be understood that the piston which comprises the 45 members 60 and 62^a rotates with the said handle and that in consequence thereof it moves longitudinally in said handle toward the rear thereof simultaneously with the rotatory and longitudinal movement of the 50 handle. Such rearward longitudinal movements of the handle 1 and the discharge tube and the part 30 secured thereto is in opposition to the pressure exerted by the spring 56. Consequently as soon as the handle 1 has 55 been turned sufficiently to carry the cam projections 51 through a half revolution they will again move into engagement with the cams 50 under the influence of the spring 56 which at such time causes longitudinal forward movement of the part 1, the discharge 60 tube and the part 30 secured to the latter, so that the opening 13 is closed by the forward pointed end 14 of the said tube.

When the plastic material has been driven 65 from the handle 1 by the rear longitudinal

movement of the piston the elastic disk 62^a will be found to occupy the space formed by the enlargement 2 of the handle 1. In placing or inserting the disk 62^a in the forward open end of the part 1 before the same is 70 closed by the closing cap 4, it is compressed, consequently when it is moved into the enlarged portion 2 of the handle 1 it expands and cannot readily be removed therefrom.

The idea of providing a construction of 75 handle having means to prevent the ready removal of the disk 62^a after the material has been emptied is to prevent the handle from being used a second time. It is the purpose that the material, such as soap, to 80 be dispensed shall be placed in a handle such as the handle 1 and the inner forward end thereof closed by means of a new elastic disk 62^a which handle may then be used and substituted for a handle 1 from which all of the 85 soap material has been discharged, such used handle being thrown away.

I claim:

1. In a device for dispensing liquid, semi-liquid and plastic material, the combination 90 of a receptacle for holding said material, a discharge tube leading from the interior of said receptacle and projecting a distance beyond the forward end thereof, the said material being discharged through said tube, 95 a tube into which the forward, projecting part of said discharge tube extends and into which the said material escapes from the latter, and means interposed between the said tubes for preventing any of said material 100 from escaping rearwardly through said second named tube.

2. In a device for dispensing liquid, semi-liquid and plastic material, the combination 105 of a receptacle for holding said material, a discharge tube leading from the interior of said receptacle and projecting beyond the forward end thereof, a tube into which the forward end of said discharge tube projects, means for expelling the material from said 110 receptacle through said discharge tube and the forward end of said second named tube, and means interposed between a portion of said discharge tube and said second named tube for preventing the passage of any of 115 said material rearwardly through the latter.

3. In a device for dispensing liquid, semi-liquid and plastic material, the combination 120 of a receptacle for holding the said material, a discharge tube extending from the interior of said receptacle and projecting beyond the forward end thereof for discharging the said material from said receptacle, an annular wall secured to said tube and forming an annular chamber encircling the same, a tube 125 into which the projecting part of said discharge tube extends, the rear end of said tube having an enlarged portion forming a chamber which encircles a portion of the projecting part of said discharge tube, and 130

- packing material within said chamber forming a water-tight joint between the projecting part of said discharge tube and the said enlarged portion of the second named tube.
- 5 4. In a device for dispensing liquid, semi-liquid and plastic material, the combination of a receptacle for holding said material, a discharge tube extending from the interior of said receptacle and projecting beyond the 10 forward end thereof through which the material escapes from said receptacle, a wall secured to said discharge tube and spaced therefrom to form a chamber around a portion of the projecting part of said discharge 15 tube, a tube into which said projecting part extends, the rear end of said tube extending into said chamber, and means interposed between the said tubes for preventing the escape of material into said chamber.
- 20 5. In a device for dispensing liquid, semi-liquid and plastic material, the combination of a receptacle for holding said material, a discharge tube extending from the interior of said receptacle and projecting beyond the 25 forward end thereof through which the material escapes from said receptacle, the forward end of said tube terminating in a valve portion, a wall secured to said discharge tube and spaced therefrom to form a chamber around a portion of the projecting part 30 thereof, a tube into which said discharge tube extends, the forward end of said tube having an opening through which the material discharged from said discharge tube escapes, and the rear end of said tube extending into said chamber, means interposed between said tubes for preventing the escape of material rearwardly through the second named tube into said chamber, and means 35 for causing reciprocating movement of said discharge tube, substantially as described.
6. In a device for dispensing liquid, semi-liquid and plastic material, the combination of a receptacle for holding the said material, a discharge tube extending from the interior of said receptacle and projecting beyond the 45 forward end thereof for discharging the said material from said receptacle, said discharge tube terminating at its forward end in a valve portion and having secured thereto a member having an annular part spaced from a portion of the said projecting part to form an annular chamber surrounding the said projecting part, said annular part having at 50 its forward edge a laterally extending flange, a body portion comprising an annular member and two parallel transversely extending plates situated therein, an annular spacing member situated between the said plates and 55 surrounding the said annular part, the rear end portion of said spacing member being provided with a shoulder, a tube into which the projecting part of said discharge tube extends, the forward end of said tube being 60 provided with an opening for the escape of 65 material delivered from the said discharge tube and the rear end thereof projecting into the said annular chamber, and said tube being rigidly secured to the forward one of the said transversely extending plates, resilient 70 means interposed between the said annular wall and the said spacing member for holding the said discharge tube in forward position with the valve portion thereof closing the opening in the forward end of said second named tube, and means for causing rearward movement of said discharge tube in opposition to the action of said resilient means, substantially as described.
7. In a device for dispensing liquid, semi-liquid and plastic material, the combination of a receptacle for holding the said material, a discharge tube extending from the interior of said receptacle and projecting beyond the 75 forward end thereof for discharging the said material from said receptacle, said tube being provided at its forward end with a pointed valve portion and having discharge openings adjacent to its forward end, and the said tube also having secured thereto an 80 annular wall providing an annular chamber surrounding a portion of said projecting part, said annular wall being provided with a lateral flange at its forward edge, a hollow body portion provided with a couple of parallel spaced plates extending transversely thereof, an annular spacing member situated within the said hollow member and between the said transversely extending plates, the 85 rear portion of said spacing member being provided with a shoulder, a tube fixedly secured to the forward end of the said transverse plates, said tube being provided with a discharge opening at its forward end and with an enlargement at its rear end which 90 projects into the said annular chamber, packing material interposed between the enlarged portion of said second named tube and the projecting part of the said discharge tube, means for securing the said receptacle and 95 the said head, a spring interposed between the flange upon the said annular wall and the shoulder upon the said spacing member for holding the said discharge tube in forward position to close the discharge opening 100 in the said second named tube, and means for causing rearward movement of the said discharge tube, substantially as described.
8. In a device for dispensing liquid, semi-liquid and plastic material, the combination of a receptacle for holding said material, said receptacle having an enlargement at its 105 rear end to form an enlarged space therein, a discharge tube leading from said receptacle and projecting beyond the forward end thereof, the portion of said discharge tube within the said receptacle being screw threaded, a piston within the said receptacle 110 which piston has screw threaded engagement with the said discharge tube, and the said 115
- 120
- 125
- 130

piston comprising elastic and non-elastic portions, the said elastic portion being compressed when inserted within the said receptacle, means for rotatably connecting the 5 said receptacle with the said discharge tube, the rotation of the said receptacle with respect to the said discharge tube causing rotation of the said piston with respect thereto by reason of the friction between the 10 said piston and the interior surface of the said receptacle, whereby the said piston is caused to move toward the rear of the said receptacle upon the rotation thereof, the said elastic portion, when the said piston reaches 15 the rear end of the said receptacle, entering the said enlarged portion and expanding to fill the same, substantially as described.

9. In a device for dispensing liquid, semi-liquid and plastic material, the combination 20 of a receptacle for holding said material, a discharge tube extending from said receptacle for discharging the said material there-

from, the said discharge tube within the said receptacle being screw threaded, a piston situated within the said receptacle and having screw threaded engagement with the said screw threaded tube and frictional engagement with the interior surface of said receptacle, means for connecting the said receptacle and said discharge tube whereby they 25 are relatively rotatable, such relative rotation causing relative rotation of the piston and discharge tube to effect axial movement of said piston upon said discharge tube and the said piston comprising an elastic annular 30 portion having an inwardly extending annular flange at one edge for engaging the said screw threaded discharge tube, substantially as and for the purpose described.

In testimony that I claim the foregoing as 40 my invention, I have hereunto set my hand this 16th day of September, A. D., 1918.

GUSTAVE A. LOEBEN.
